SHAVING INSTRUMENT

Jesse D. Langdon, Long Beach, Calif.

Application October 24, 1947, Serial No. 781,975

7 Claims. (Cl. 30—73)

1

The present invention relates to shaving instruments, safety razors and the like, and aims to provide means to adjust the angle of incidence at which the razor blade is held, and provide other features instrumental in meeting the following objects and purposes:

To provide a guide in conjunction with a blade and guard for the cutting edge thereof whereby the cutting edge is held at a substantially constant angle with relation to the surface to be shaved and whereby the angle of incidence may be changed within certain practical limits by the movement of the handle of the instrument.

To provide a tensioned adjustment of the angle of incidence with relation to a guard bar disposed forwardly of the cutting edge of a shaving blade.

Other and further objects and purposes will appear during the progress of the following specification; as illustrated by the drawings which shown one method of reduction to practice which may be changed within the scope of the claims.

Of the drawings:

Fig. 1 shows the fully assembled shaving instruments in perspective viewed at a slight angle taken from the handle side.

Fig. 2 is a central transverse section of the guard plate, razor blade and a fragment of the handle in assembled position.

Fig. 3 is a plan view of the guard plate looking toward the convex side.

Fig. 4 is a plan view looking toward the convex side of the guard plate.

Fig. 5 is a longitudinal section of the guard plate looking as at 5—5, Fig. 4.

This application is a continuation in part of Sér. No. 578,444, filed Feb. 17, 1945, now Patent 2,434,275, granted January 13, 1948.

Fig. 1 illustrates the relative position of the various elements constituting the structure of the shaving instrument comprising the invention including: a handle 1, a curved blade plate 2 having a threaded stud bolt 3 attached to the center thereof. The plate 2 has four blade retainers 4—4—4—4 integral with and partly cut away from plate 2 and standing at an angle lateral to the plane of plate 2 and projecting from the concave side of the plate 2. Angle adjusters 5—5 are formed by partly cut away portions and also integral with plate 2. The guides 5—5 are suspended and extended laterally from both ends of the plate 2. The guard bars 6—6 are contiguous with the angle guides 5—5 and are extended beyond and lie

parallel with and longitudinally of the plate 2, leaving an open slot between the plate 2 and the guard 6 on both sides of the plate 2. The double edged razor blade 7 is held in operative position between the proximate end of the handle 1 and the concave side of the plate 2.

It will be observed that Figs. 1 and 2 illustrate the blade as being held in conformity with the concave side of plate 2 by the proximate end of the handle 1. The plate 2 must therefore be stiffer than the blade 7 which is more flexible than plate 2, otherwise plate 2 would have to be distorted in order to be assembled with the blade 7.

Fig. 2 illustrates in detail the handle 1 adjustably attached to plate 2 by means of threaded stud 3. The blade retainers 4—4—4—4 serve to hold the blade 7 in parallelogram with the guard bars 6—6 and angle adjusting guides 5—5.

Fig. 3 being a plan of the plate 2 viewed from the convex side, illustrates the manner in which the blade retainers 4—4—4—4 are cut away from the body of the plate 2 and also shows how the ends of the plate 2 are extended to support the angle adjusting guides 5—5 and guard bars 6—6.

Fig. 4 being a plan of plate 2 viewed from the concave side shows the stud bolt 3 and the blade retainers 4—4—4—4 standing away from the concave side of the plate 2.

Fig. 5 being a longitudinal section viewed as at 5—5, Fig. 4, shows the plate 2 having stud 3 riveted therethru, blade retainers 4—4—4—4 standing substantially laterally to the plane of plate 2, and also the back side of the angle adjusters 5—5 standing away from the convex side of the plate 2.

The new features and results as well as the novelty of the instant invention are as follows:

Handle 1: (a) Is preferably provided with a convex end proximate to and having a radius concomitant to the curvature of the blade plate 2, whereby the blade 7 is urged to conform with the concave side of the plate 2. (b) The handle 1 being the sole means of holding the assembled relationship of the plate 2 and the razor blade 7 whereby the latter is left free of any impediment to the passage of lather, air, follicular scale and dirt between the cutting edges of the razor 7 and the guard bars 6—6. The net result being a more sanitary and easily cleaned instrument as well as non-clogging guard means for the cutting edge of the blade 7.

The blade supporting plate 2 is preferably made of a single piece of resilient material, having formed integrally contiguous therewith: (a)

Blade retainers 4—4—4—4 forming aligning means for the blade 7 and holding the same parallelogram in plan. (b) Extending from the two ends of the plate 2 the variable angle adjustment means formed by guides 5—5 permit a slight change in the angle of incidence of the blade by changing the position of the handle according to the choice of the operator with a view to changing the depth of the cut and closeness of the shave.

Stud 3 provides means whereby the various elements of the shaving instrument are held in operative assembly in conjunction with the handle 1.

Blade retainers 4—4—4—4 preferably are integral extensions partly cut away from a single sheet of metal, such as spring bronze or the like and are extended substantially at right angles to the concave side of the plate 2 in a position to contact the two ends of the blade 7 which is shown to have an extension at either end lying between the retainers 4—4—4—4, thus preventing lateral or longitudinal movement of the blade and holding the same in alignment with the plate 2 including the angle adjusters 5—5 and the guard bars 6—6, all elements being held parallelogram in plan.

Angle adjusters 5—5 extended laterally from the two ends of plate 2 form spring arms suspending the guard bars 6—6 in parallax relationship to the flat sides and cutting edges only of the blade 7 whereby a change of position of both the angle adjusters 5—5 and the guard bars 6—6 with relation to the cutting edges of the blade 7 is permitted according to the angle at which the handle is held by the operator.

Guard bars 6—6 being flexibly suspended by the angle adjusters 5—5 are preferably formed of the self material of the plate 2, said guard bars 6—6 and the angle adjusters moving in unison with the angle at which the handle is held and according to the pressure exerted by the operator when using a shaving instrument.

Having described the invention, the new elements thereof instrumental in bringing about the new results obtained by the instant shaving instrument the following claims are made:

1. A shaving instrument comprising a blade having a cutting edge, a guard plate, handle means urging the guard plate in contact with a flat side of said blade, a spring-tensioned guard bar spaced forwardly of the edge of said blade, spring means attached to and extended at a tangent forwardly of that side of said plate that does not contact said blade, said spring means having a bend producing a tangent portion converging toward said plate, said converging portion being extended beyond the edge of said blade for holding the guard bar in operative position spaced away from the edge of said blade, the converging portion of the spring means adjacent said guard bar serving as guide means touching a surface to be shaved to influence the angle between the shaving surface, said guard bar and the cutting edge of said blade.

2. An article of manufacture comprising a guard plate for a shaving instrument formed of a single piece of resilient sheet material and having a central portion for contacting a flat surface of a double edged blade, means for attaching a handle to said plate, a narrow portion at each end of said plate extended at a tangent forwardly of the surface of said plate opposite the attaching means for said handle and being extended from a point near a longitudinal median

line of said plate, guard bars formed integral with and extended between the ends of the narrow portions extended from the opposite ends of the plate and being spaced away from the opposite edges of said blade when assembled with said plate.

3. An article of manufacture consisting of a resilient sheet metal plate configurated to form a guard plate adaptable to be assembled with a flat blade having a cutting edge for shaving a surface and comprising; a plate having a slot therethru, the inner border of said slot defined by a section of said plate providing a face for contacting a blade near and along said cutting edge, when assembled with said plate, the ends of the slot being defined by substantially narrow strip portions paralleling each other and being cut free for a distance along the opposite ends of the plate, said narrow strips having proximal ends attached to narrow extensions from the opposite ends of said plate, other narrow strips being cut free of the said plate, inwardly of the first strips, and extended at an angle to the first named strips from points inwardly of said slot, the free portions of the last named strips projecting at an angle from said plate and in substantially the same direction as a handle attaching means attached to and projecting from said plate, said second named strips providing aligning means for contacting the two ends of a flat blade inserted therebetween to hold an edged portion of the blade in alignment with the inner edge of said slot means, said first named strips forming resilient arms supporting a guard bar ahead of said cutting edge and defining the outer border of said slot.

4. An article of manufacture as defined by claim 3, the first named strips supporting the guard bar being looped forwardly of that face of the plate, that is away from the handle attaching means, whereby the portion of the loop that is toward the guard bar will contact the surface to be shaved.

5. Guard means for a shaving instrument of the nature described: comprising a rectangular plate formed with a central plate portion having relatively narrow oppositely extended ends, arms extended laterally of the narrow ends and being bent away from the ends at a tangent forwardly of the top side of the plate, then having another bend producing a portion converging toward the border of the plate that parallels guard bar means attached to the ends of said arms, a space forming slot means between the bar means and said central plate portion; said arms forming guide means projecting forwardly and lying at an angle to the top face of the plate, the bottom face of the plate adapted to receive a flat blade having a cutting edge, the cutting edge projecting toward the slot and said bar means whereby said bar means being positioned ahead of said cutting edge act in conjunction with said arms to guide said cutting edge according to the angle of that portion of the arms that is attached to the two ends of said central plate and said bar means.

6. A device as of claim 5; the arms supporting the guard bars being extended forwardly of the face of the plate that is opposite to handle attaching means projecting from said plate, said arms then being bent and extended at a tangent approaching the same face, and being adapted to first contact the shaving surface ahead of the proximate face of said plate.

7. A device as of claim 5; wherein the central

plate portion is curved, a handle being adjustably attached to the plate and projecting from the concave side thereof, the flat blade being held in position between the proximate end of the handle and the concave side of said plate, whereby the blade is urged to a curvature concomitant with the curve of the plate.
